US00D907951S

(12) **United States Design Patent** (10) **Patent No.:** **US D907,951 S**
(45) **Date of Patent:** **** Jan. 19, 2021**

(54) **OVEN**

(71) Applicant: **Furrion Property Holding Limited**,
Hong Kong (HK)

(72) Inventors: **Steven Neill Bell**, Hong Kong (HK);
Matthew David Fidler, Hong Kong (HK); **Bernard San Lap Lo**, Hong Kong (HK); **Wesley King Juen Tong**, Hong Kong (HK); **Yuk Ying Wong**, Hong Kong (HK); **Hung Wing Yee**, Hong Kong (HK)

(73) Assignee: **Furrion Property Holding Limited**,
Hong Kong (HK)

(**) Term: **15 Years**

(21) Appl. No.: **29/675,714**

(22) Filed: **Jan. 4, 2019**

(51) **LOC (13) Cl.** **07-02**

(52) **U.S. Cl.**

Primary Examiner — Dana K Weiland

Assistant Examiner — Messina L Smith

(74) *Attorney, Agent, or Firm* — Faegre Drinker Biddle & Reath LLP

CLAIM

The ornamental design for an oven, as shown and described.

DESCRIPTION

FIG. 1 is a front perspective view of an oven, illustrating our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the oven that form no part of the claimed design.

1 Claim, 7 Drawing Sheets
